UNITED STATES PATENT OFFICE.

FRANK J. CROUCH AND CHARLES P. CHURCH, OF SEATTLE, WASHINGTON.

INTERNAL-COMBUSTION ENGINE.

No. 893,058.

Specification of Letters Patent.

Patented July 14, 1908.

Application filed June 12, 1907. Serial No. 378,587.

To all whom it may concern:

Be it known that we, FRANK J. CROUCH and CHARLES P. CHURCH, citizens of the United States, residing at Seattle, in the county of King and State of Washington, have invented a new and useful Internal-Combustion Engine, of which the following is a specification.

This invention relates to internal combustion engines of that type in which the head of the explosion chamber is adjustable for the purpose of varying the cubic content of the cylinder.

The principal object of the invention is to provide an adjustable head that is recessed at one side at a point opposite the controlling valve of the cylinder, so that the head may be adjustable toward and from the piston without interfering with the operation of the valve while the inlet and exhaust port will remain at the end of the explosion chamber.

A still further object of the invention is to provide a device of this class in which a single valve arranged adjacent the end of the explosion chamber is employed for controlling both the inlet of the explosive charge and the exhaust of the products of combustion, the adjustable cylinder head being recessed at a point opposite the valve, and the spark plug being so arranged that the terminals of the plug are exposed at one wall of the recess.

With these and other objects in view, as will more fully hereinafter appear, the invention consists in certain novel features of construction and arrangement of parts, herein-after fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a sectional elevation of an internal combustion engine constructed in accordance with the invention. Fig. 2 is an end elevation of a portion of the same, partly in section on the line 2—2 of Fig. 1. Fig. 3 is a sectional view of the valve open to permit the passage of the exhaust. Fig. 4 is a similar view showing the exhaust closed and the inlet port open.

Similar numerals of reference are employed

to indicate corresponding parts throughout the several figures of the drawings.

The engine is provided with a suitable base for the support of the crank casing 10 and cylinder 11, and at the ends of the crank casing are arranged bearings for a main shaft 15 which is connected in the usual manner to the trunk piston 16.

The cylinder is surrounded by a suitable cooling jacket 18, and at the working end is bolted a spider 19 that is provided with a centrally arranged opening threaded for the reception of a handled screw 20.

Fitting within the working end of the cylinder is a movable head 21, the diameter of which is preferably equal to that of the piston, and said movable head may be adjusted toward and from the piston in order to vary the space in which the explosive charge is compressed, and, also, to vary the capacity or cubic content of the cylinder, and the quantity of gases which it will admit for a working charge. The movable head is swiveled to the inner end of the screw 20, so that it may be freely moved in the direction of the length of the cylinder without turning.

At one side of the movable head is formed a recess 22 into which projects the end of a sparking plug 23 of any ordinary construction, the plug being movable with the head.

At one side of the cylinder is formed a boss 24 that is bored out to receive a cylindrical lining 25, that is preferably threaded at one end to screw into female threads formed in the boss, in order that the lining may be properly held in place. The inner end of the lining is beveled off to form a seat for a puppet valve 27 carried by a stem 28 at the outer end of which are adjustable nuts or sleeves 29 to receive the end of a cam actuated lever 30. Leading through the lining is an exhaust port 32, and an inlet port 33, the latter communicating with a carburetor or other source of supply for the explosive charge.

Secured to the stem 28 is a piston valve 34 that is provided with openings extending from end to end to permit the free passage of gases. This valve controls both the inlet port and the exhaust port and may be moved to close or open either of them.

The engine frame is provided with bearings for a cam shaft 40 on which is a gear wheel 41 intermeshing with a pinion 42 on the main crank shaft, the pinion being one-half the diameter of the gear. The shaft 40

carries a cam 43 having three cam surfaces, 44, 45 and 46, the portions 45 and 46 each occupying approximately ninety degrees, while the portion 44 of the cam extends approximately through an arc of one hundred and eighty degrees. Bearing against the cam is a roller 47 that is carried by the lever 30.

When the parts are in the position shown in Fig. 1, a charge has been compressed in the upper portion of the cylinder and is about to be ignited by the sparking plug. When this occurs, the piston is moving down and during the half revolution of the crank, 15 the cam 43 is moved to the extent of a fourth revolution, so that the portions 45 of the cam will be brought to a position against the roller 47 and this will move the valve stem 28 for the purpose of opening the puppet valve 27, 20 so that during the next half stroke of the piston, while the latter is moving outward from the crank shaft to the initial position, the gases and products of combustion will be forced out past the valve and through the 25 sleeve and the port 36 to the exhaust. By the time the parts have arrived at this position, the cam surface 46 will have reached the roller 47, and the valve 27 will be moved further into the cylinder, while the valve 34 30 will have been shifted to a position to close the exhaust port 32 and open the inlet port 33 and the parts are held in this position during the next stroke of the piston in the direction of the crank shaft, this being a suction 35 stroke on which a fresh charge is drawn into the cylinder. The parts remain in this position until the suction stroke is complete, by which time the cam will have made another quarter of a revolution, and the roller will have descended from the section 46 of the cam to the portion 44 thereof, and the apparatus will be moved to the positions shown in Fig. 1 and held in this position during the subsequent compression and working strokes. 40

45 In engines of this type it is often extremely difficult to compress the charge by hand cranking, and for this reason the movable head 21 may be adjusted outward from the piston in order to reduce the extent of compression, and thus allow the engine to be started instantly. After the engine has started, the screw may be turned for the pur-

pose of increasing or decreasing the compression, as desired, and by altering the cubic content of the cylinder, the quantity of gas admitted is altered, and the extent to which the compression is carried is varied, so that both the speed and the power of the engine may be accurately adjusted.

It will be seen that by employing the same 60 passage for both the inlet and the exhaust, the heat of the exhaust will raise the temperature of the walls of the passage in the valve to such an extent that any liquid which may remain in the explosive charge will be vaporized, thus adding to the efficiency of the 65 charge.

We claim:—

1. In an internal combustion engine, a cylinder having a valve controlled port extending through one wall thereof, a piston in the cylinder, and an explosion chamber head adjustable to vary the cubic content of the cylinder, said head being recessed to clear said port. 75

2. In an internal combustion engine, a cylinder, a piston therein, there being a port or passage extending through the wall of the cylinder at a point adjacent the end of the explosion chamber, said port controlling both the inlet and exhaust of the charge, and an adjustable explosion chamber head recessed to clear such port or passage. 80

3. In an internal combustion engine, a cylinder having a port extending through one wall thereof, said port being disposed adjacent the end of the explosion chamber and controlling both the inlet and exhaust of the charge, a valve for closing said port, a piston in the cylinder, an explosion chamber head adjustable to vary the cubic content of the cylinder, said head being recessed to clear the port and valve, a spark plug carried by the head and having sparking terminals in the recess, and means for adjusting said head. 90

In testimony that we claim the foregoing as our own, we have hereto affixed our signatures in the presence of two witnesses.

FRANK J. CROUCH.
CHARLES P. CHURCH.
